(57) **CLAIM**

The ornamental design for a knee, shin, and ankle protection sleeve, as shown and described.

DESCRIPTION

FIG. 1 is a perspective view of a knee, shin, and ankle protection sleeve showing my new design; FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines illustrating a foot in FIG. 1 depict environment and form no part of the claimed design. The remaining broken lines in the drawings depict portions of the knee, shin, and ankle protection sleeve that form no part of the claimed design.

1 Claim, 4 Drawing Sheets
